UNITED STATES PATENT OFFICE.

STANLEY C. GILTHORPE, OF NEW ORLEANS, LOUISIANA, ASSIGNOR OF ONE-THIRD TO RICHARD J. BEQUETTE AND ONE-THIRD TO HUNTER C. LEAKE, BOTH OF NEW ORLEANS, LOUISIANA.

DRILL-HEAD FOR WELL-DRILLING APPARATUS.

1,391,626.

Specification of Letters Patent. Patented Sept. 20, 1921.

Application filed April 27, 1920, Serial No. 377,039. Renewed February 24, 1921. Serial No. 447,555.

To all whom it may concern:

Be it known that I, STANLEY C. GILTHORPE, a citizen of the United States, and a resident of New Orleans, in the parish of 5 Orleans and State of Louisiana, have invented a new and Improved Drill-Head for Well-Drilling Apparatus, of which the following is a full, clear, and exact description.

This invention relates generally to the 10 class of earth boring apparatus and has particular reference to an improvement in drill heads for use in the drilling of oil or gas wells.

With the apparatus and tools now in use 15 for this class of work, the operation is very slow and tedious and at this time it is a known fact that the consumption of petroleum and its products far exceeds the production.

20 The principal object therefore of the present invention is to provide an improved means for efficiently and expeditiously sinking wells to greatly increase the production and reduce the labor incident thereto, to a 25 minimum.

An other object of the invention is to provide a well drilling apparatus which includes means for constantly playing streams of water on the cutting elements in order to 30 minimize the danger and consequent loss by fire which might be generated by sparks due to the contact of said elements with rocks or other solid substances.

A further object of the invention is to provide 35 a drill head which is insertible through and removable from a well casing for working association therewith, without the necessity of removing the casing.

A still further object of the invention is to 40 provide a drill head which reduces the probability of broken casings to a minimum practically resulting in the elimination of costly fishing tools and the extra labor incident to their use.

45 A further object of the invention is to provide a comparatively simple and inexpensive apparatus which includes means for effectively controlling the drill head from the ground surface.

50 With the above recited and other objects in view some of which will appear hereafter as the nature, purpose and operation of the apparatus is more clearly understood, reference is made to the following detailed de-

scription, claims and accompanying drawings which form a part of this application, and in which,

Figure 1 is a side elevation of the apparatus positioned in a well for working operation.

Fig. 2 is an enlarged vertical sectional view through the drill head illustrating the same operatively associated with the lower portion of a well casing.

Fig. 3 is an enlarged vertical sectional view through a portion of a well casing illustrating the manner of removing or inserting the drill head therein.

Fig. 4 is an enlarged detail horizontal sectional view therethrough, taken approximately on the line 4-4 of Fig. 2.

Fig. 5 is a similar sectional view taken approximately on the line 5-5 of Fig. 2.

Fig. 6 is a like view taken approximately on the line 6-6 of Fig. 2.

Fig. 7 is a fragmentary transverse sectional view through one of the side bits or cutters, illustrating the relation of the scraper blades thereto.

Referring to the drawings in detail, similar characters of reference denote like parts throughout the several views thereof. In Fig. 1 a well casing is provided which consists of a plurality of casing sections 10, said sections being added as the depth of 85 the well increases. The casing sections are secured together in any well known manner and the casing is adapted to be continuously rotated by the usual turn-table or any other suitable mechanism of this character which 90 is positioned at the top of the well.

In order to adapt the well casing for use in connection with the improved drill head provided, the lowermost casing section is formed with an annular flange 11 on its inner periphery and a plurality of radial openings 12 immediately thereabove. A reamer 13 of substantially frusto-conical formation is provided and is formed with a vertical bore 14 having a restricted portion 15 at its 100 lower end, the juncture of said bores forming a shoulder 15^a. The enlarged portion of the bore 14 is of substantially the same diameter as the outer diameter of the well casing section and the restricted portion 15 of the bore 105 is substantially of the same diameter as the inner periphery of the flange 11. The enlarged portion of the bore is provided with

radial recesses 16 which are adapted to align with the openings 12 to constitute keeper openings for a purpose to be hereafter described. The outer frusto-conical surface of 5 the reamer is preferably provided with a plurality of vertical rows of cutting teeth 17. A drill head is provided for detachable association with the lowermost casing section and the same comprises a permanent member 10 18 and a rotary member 19. The permanent member 18 is built up from a plurality of cylindrical sections including an upper section 20, an intermediate section 21, and a lower section 22. A head 23 is threadedly 15 engaged over the upper open extremity of the uppermost section 20 and said head is provided with a peripheral flange 24 which is of substantially the same diameter as the inner diameter of the well casing. The flange 24 is designed to rest upon the flange 11 of the lowermost casing section, said flange 11 serving as a means for limiting the passage of the drill head through the lower end of the casing. The head 23 is provided 20 with a plurality of radial rectangular bores 24* the inner portions of which terminate in reduced round bores 25. A vertical opening 26 centrally of the head communicates with the bores 25, and a yoke 27 straddles the opening 26 and projects upwardly from the head 23. A rectangular bolt 28, having a reduced stem 29 at its inner end, is arranged for sliding movement in each radial bore 24*. The inner end of each stem is apertured as 25 at 30 for the reception of the end link of a chain section 31. The innermost link of a hoisting chain 32 is received by the yoke 27 and said link serves as a common connection for the opposite end of each chain section 30 31. An expansion spring 33 surrounds the stem 29 of each bolt and is disposed between the shoulder formed at the juncture of the stem with the bolt and the shoulder formed at the juncture of the bores 24* and 25. The 35 springs 33 normally effect radial projection of the bolts 28 from the head, through the openings 12 in the casing section and into the recesses 16 of the reamer in order to lock the drill head, casing and reamer for simultaneous movements. From this construction it will be seen that when it is desired to remove the drill head from the well casing, the initial lift on the hoisting chain 32 will exert a pull on the chain sections 31 to retract 40 the bolts 28 within the bores 24* of the head and disengage the same from the openings 12 and recesses 16. Further upward pull on the chain will effect engagement of the lowermost link with the yoke to lift the drill head for withdrawing the same from the casing.

The head 23 is vertically apertured for the reception of a pipe section 34 which passes therethrough and constitutes a supply manifold for the reception of water supplied

thereto from the top of the well through the well casing. The uppermost section 20 of the permanent section 18 is provided with a horizontal wall 35 adjacent its lower end and said wall is apertured for the passage of 70 a plurality of water supply pipes 36. The intermediate section 21 is provided with spaced horizontal walls 37 and 38 adjacent its lower end, said walls defining a water reservoir 39 for the reception of water supplied thereto by the pipes 36 which communicate with said reservoir through openings in the wall 37. The space defined between the horizontal walls 35 and 37 constitutes a motor housing 40 in which is supported by 75 means of brackets 41, a suitable motor 42 of either the electric or compressed air type. The supply of current or air to the motor is received through the conduit 43 which passes through openings in the horizontal wall 35 80 and the head 23 respectively, to a source of supply at the top of the well. The lowermost section 22 of the permanent drill head member 18 is provided with spaced horizontal walls 44 and 45, the space between the walls 90 38 and 44 providing a fly wheel housing 46. The horizontal walls 37, 38, 44 and 45 are centrally apertured for the reception of the motor drive shaft 48 which passes therethrough, the said openings being provided 95 with any suitable packing (not shown) to prevent leakage. A fly wheel 49 is mounted on the drive shaft 48 and operates in the fly wheel housing 46 which is provided with a filling opening 50 having a removable plug 100 to permit of the insertion of lubricating oil thereto. A gear 51 is keyed to the drive shaft and is disposed within the transmission housing 47 as clearly illustrated in Fig. 2 of the drawings. A plurality of vertical stub 105 shafts 52 having gears 53 keyed thereto, are disposed radially with respect to the main drive shaft and are extended through the horizontal wall 45. The gears 53 of said stub shafts respectively mesh with the gear 110 51 on the drive shaft. The lower extremities of the stub shafts have keyed thereto the pinions 54 which are disposed below the wall 45.

The rotatable member 19 of the drill head 115 is constructed of inner and outer sections 55 and 56, the former received by the bore formed in the outer end of the latter. The outer member is provided with an upper closed end wall 57 which is provided with a 120 vertical peripheral boss 58 having an annular groove 59 on its outer surface. The lower extremity of the lowermost section of the member 22 is provided with a number of inwardly projecting trunnions 60, which 125 are adapted to operate in the groove 59 whereby the rotatable member 19 of the drill head is revolvably associated with the permanent section 18. The upper end wall 57 of the outer member is apertured for the re- 130

ception of the drive shaft and a ring gear 61 meshing with the pinions is secured to said upper wall 57, whereby power from the drive shaft is transmitted through the gears 51, 53, 54 and 61 to the rotatable section 19 of the drill head. The inner member 55 is provided with a vertical bore 62 through which the lower end of the drive shaft extends. A conical pilot bit 63 having spirally arranged cutting teeth 64 is carried by the free extremity of the drive shaft and is disposed centrally of the outer end of the inner member, said pilot bit being detachably associated with the drive shaft to permit of its ready removal or application thereto. The inner member is provided with a plurality of radially disposed recesses 65 for the reception of the side frusto-conical bits or cutters 66 which are mounted upon the stub shafts 67. The outer surfaces of the side bits or cutters are provided with annular rows of cutting teeth 66^a. The stub shafts 67 have their bearing in both the inner and outer members of the rotary head as illustrated. The drive shaft is provided with a beveled gear 68 which is keyed thereto and is disposed directly above the upper extremity of the inner member. Radially disposed stub shafts 69 having threaded inner extremities 70 extend through apertures 71 in the outer member and are anchored in the threaded sockets 72 of the inner member, thereby functioning as an auxiliary means for securing the inner and outer sections 55 and 56 together. A gear having oppositely beveled faces provided with beveled gear teeth 73 and 74 is mounted for rotation upon each stub shaft 69, with the teeth 73 thereof meshing with the beveled gear 68 on the drive shaft. The gear teeth 74 mesh with a beveled pinion 75 on the stub shaft 67 for transmitting rotations to the side bits or cutters 66.

In order to provide means for playing streams of water on the cutters or bits, to prevent the generation of sparks thereby, a water receiving chamber 76 is provided in the inner member 55 and is provided with ports 77 communicating with the recesses 65. In order to establish communication between the water reservoir 39 and the water receiving chamber 76, the drive shaft is provided with a central opening 78 which extends from the water reservoir 39 to the water receiving chamber 76. The said opening 78 is provided with branch ports 79 at its opposite ends which extend through the shaft to its outer periphery to permit of the passage of water to and from the same. The upper portion of the recess in the outer member 56 constitutes an oil reservoir 80 which receives its supply of lubricating oil through an opening 81 in its upper closed end, said opening being normally closed by a removable plug 82. The lubricating oil feeds

by gravity the bearings of the different gears as will be readily understood from the showing in Fig. 2 of the drawing.

In order to provide means for freeing the teeth 66^a of the cutters 66 from particles of earth or rock which might adhere thereto, use is made of scraper blades 83 which are adjustably mounted on the inner member 55 at opposite sides of the recesses 65 by means of set screws 84. The blades 83 also serve as means for preventing the entrance of particles of earth or rock into the recesses 65 which might clog or hinder the operation of the side cutters.

In use and operation of the apparatus, the drill head is initially locked to the lower casing section by the engagement of the bolts 28 in the openings and recesses 12 and 16, and the motor 42 is started. The pilot bit 63 is driven at motor speed due to the fact that it is keyed directly to the motor drive shaft 48. The revolute member 19 being driven at a relatively reduced rate of speed through the gear train. The side bits while rotating with the revolute section are each driven through their train of gears from the master gear 68 at an increased rate of speed. The pilot bit initially breaks the ground and the side bits widen the opening. The well casing which is constantly revolving by a turntable or other suitable mechanism at the surface still further enlarges the well through the medium of the reamer 13. Should the drill head fail to operate or should any of its elements become broken, it is readily removable through the casing by the hoisting chain 32 and when repaired is as readily replaced by reinserting the same through the casing. To reassociate the drill head with the lower extremity of the lower casing section, the same is lowered by the hoisting chain until the flange 24 contacts with the flange 11. As the flange 24 of the drill head contacts with the flange 11 of the casing, the springs 33 will function to project the bolts 28 into the openings 12 in the casing and the radial keeper openings 16 of the reamer.

While there has been shown and described a single and preferred embodiment of the invention, it is understood that the same is merely illustrative of one manner in which the same may be reduced to practice and such alterations or changes which fall within the scope of the appended claims may be resorted to when found expedient.

Having thus described my invention, I claim as new and desire to secure by Letters Patent:—

1. In a well drilling apparatus, a drill head comprising a permanent section adapted to be detachably associated with a well casing for rotation therewith, and a rotary section carried by the permanent section for independent relative rotation.

2. In a well drilling apparatus, a drill head comprising a permanent section adapted to be detachably associated with a well casing for rotation therewith, a rotary section carried by the permanent section for independent relative rotation, means carried by the permanent section for driving the rotary section.
3. In a well drilling apparatus, a drill head comprising a permanent section adapted to be detachably associated with the well casing, a rotary section carried by the permanent section for independent relative rotation, a motor carried by the permanent section, a pilot bit extending from the rotary section and driven directly by the motor, a plurality of side bits mounted in the movable section and mechanism for transmitting power from the motor to the side bits for driving the same at a different speed from the pilot bit.
4. In a well drilling apparatus, the combination with a casing having a reamer mounted on its lower end, of a drill head having a plurality of drill bits, said drill head being movable through said casing and adapted to be detachably associated with the lower end thereof to dispose the drill bits from the lower end thereof.
5. In a well drilling apparatus, the combination with a casing having a reamer mounted on its lower end, of a drill head having a plurality of drill bits, said drill head being movable through said casing and adapted to be detachably associated with the lower end thereof to dispose the drill bits from the lower end thereof, and means for driving said drill head from the upper end of the casing.
6. In a well drilling apparatus, the combination with a casing having a reamer mounted on its lower end, of a drill head having a plurality of drill bits, said drill head being movable through said casing and adapted to be detachably associated with the lower end thereof to dispose the drill bits from the lower end thereof, means for driving said drill head from the upper end of the casing, and means for playing streams of water onto the drill bits while in operation.
7. In a well drilling apparatus, the combination with a casing having a reamer mounted on its lower end, of a drill head having a plurality of drill bits, said drill head being movable through said casing and adapted to be detachably associated with the lower end thereof to dispose the drill bits from the lower end thereof, means for driving said drill head from the upper end of the casing, means for playing streams of water onto the drill bits while in operation, and means for effecting disengagement of the drill head from the casing from a point at the upper end of the casing.
8. In a well drilling apparatus, a drill head having cutting elements arranged at one end, means for detachably supporting the drill head from the lower end of a well casing with its cutting elements exposed therefrom, and a reamer adapted to embrace said well casing adjacent the lower end thereof, the said means for supporting the drill head from the well casing also serving as a means for locking the reamer thereto.

STANLEY C. GILTHORPE.
